UNITED STATES PATENT OFFICE.

EDWARD M. TARPLEY, OF FRANKLIN, KENTUCKY.

FIRE SCREEN.

Application filed June 23, 1924. Serial No. 721,899.

To all whom it may concern:

Be it known that I, EDWARD M. TARPLEY, a citizen of the United States, residing at Franklin, in the county of Simpson and 5 State of Kentucky, have invented new and useful Improvements in Fire Screens, of which the following is a specification.

The object of this invention is the provision of a fire screen for open fireplaces 10 which may be swung outward from the grate and serving to protect the clothing of persons from becoming ignited from the fire therein, being so designed that it may be used as a warming rack or drying rack for 15 various articles and which, when not desired for use, may be swung upward against the fireplace and latched in a folded position.

To the attainment of the foregoing, the invention consists in the improvement as 20 hereinafter described and definitely claimed.

In the drawings:—

Figure 1 is a front elevation of a fireplace provided with the improvement.

Figure 2 is a similar view but showing the 25 screen folded against the fireplace.

Figure 3 is a sectional view on the line 3—3 of Figure 1.

Figure 4 is a perspective view of one of the corner bars employed.

30 Figure 5 is a similar view of the holding clip.

Figure 6 is a similar view of one of the angle supports for the side members of the screen.

35 Referring now to the drawings in detail, the numeral 1 designates the brickwork for an open fireplace, and 2 the mantel which is arranged at the fireplace.

In carrying out my invention I make use 40 of metal plates. Each of these plates includes a base portion 3 having a right angular flange 4 which merges into an outwardly extending flange 5. The base 3 is preferably secured to the inner edges of the vertical 45 members of the mantel 2, while the flanges 5 extend outwardly therefrom. The flanges 5 of the angle plates are provided with series of spaced round openings 6, and in each of these openings there is the offset 50 end 7 at the terminal of the angle side arms 8 of rods 9. The outer elements of the substantially U-shaped rods pass through suitable bearing openings 10 in metal bars 11. The bars are really in the nature of corner 55 posts and will hereinafter be referred to as such. The upper end of each bar 11 is

rounded outwardly, as at 12 and is provided with an opening 13. Through the aligning openings 13 there is passed the ends 15 of rod 14. The ends 15 of the rod 14 are connected by means 16 to the longitudinal bars 17 that constitute the upper members of the screen. The corner posts 11 adjacent to their lower ends are connected together and held in spaced relation by a bar or rod 18. 60 The upper members 17 preferably have their ends arranged around the angle ends 8 of the upper U-shaped guard rod 9, and the said upper rods 17 are centrally connected and held in spaced relation by elements 19. 65

Secured centrally on the mantel 2 below its shelf there is a plate 20 that has its lower end rounded upon itself to form a lip 22. The lip is designed to engage the upper 70 front rod of the construction when the latter is swung against the mantel and against the brickwork of the grate, as disclosed in Figure 2 of the drawings, and it is thought that the foregoing description, when taken 75 in connection with the drawings will fully set forth the simplicity of the construction and its advantages to those skilled in the art to which such inventions relate.

Having described the invention, I 80 claim:—

1. In combination with an open fireplace, and a mantel therefor, of a fire screen, comprising posts, rods passing freely through the posts and having angle ends which are 90 pivotally supported from the sides of the mantel, longitudinal bars loosely connected to the angle ends of the top rods, and means for suspending the screen in folded condition from beneath the shelf of the mantel. 95

2. In combination with an open fireplace and a mantel therefor, of a fire screen, including posts, rods passing freely through the posts having angle ends whose extremities are offset, angle members secured to the side stiles of the mantel in which the offset ends of the rods are pivoted, upper and lower rods secured to and spacing the posts, bars loosely connected to the angle ends of the upper one of the first mentioned rods, spacing means for said bars, and a lipped plate secured on the mantel piece below the shelf thereof to engage one of the first mentioned bars when the screen is folded upwardly and against the mantel. 105

In testimony whereof I affix my signature.
EDWARD M. TARPLEY.
